SURFACE MARKER

Lee E. Clough, Akron, Ohio, assignor to The General Tire & Rubber Company, Akron, Ohio, a corporation of Ohio

Application March 25, 1930. Serial No. 438,746

12 Claims. (Cl. 94—1.5)

This invention relates to markers for surface areas, particularly for the designation of segregated areas, traffic zones, and for traffic instruction through letter-bearing markers and design forms.

An object of this invention is to provide a marker formed of a wear-resisting rubber compound.

Another object is to provide a pavement marker which may be readily installed.

Another object is to provide a marker strip with means for easily and permanently locking the marker strip into a pavement or other surface.

A further object is to provide a marker adapted to present day traffic requirements and capable of permanent service under severe traffic conditions.

Another object is to provide a pavement marker of low initial cost and minimum maintenance expense.

Another object is to provide a pavement marker that is constructed to exclude objectionable collection of water around the anchor portion thereof.

Another object is to provide a pavement marker of flexible form that may be arranged to provide different legends suitable for instruction to traffic.

Another object is to provide a preferred embodiment of the invention is illustrated in the accompanying drawings, wherein

Figure 1 is a perspective view showing marker strips set in the pavement, with parts broken away;

Fig. 2 is a plan view of the marker strip set in the pavement;

Fig. 3 is a perspective view of the marker strip shown in section at one of the holes for receiving the expander plugs;

Fig. 4 is an elevational view of an expander plug used to secure the marker in place;

Fig. 5 is a transverse section through the marker strip embedded in the pavement, taken along lines 5—5 of Fig. 2;

Fig. 6 shows a transverse section through the marker strip, illustrating a modified form of groove liner for embedding the anchor portion of the strip in the pavement;

Fig. 7 shows a transverse section through the marker strip using a further modified form of groove liner adapted to a groove having raised and inclined shoulders;

Fig. 8 is a perspective view of the metal groove liner shown in Fig. 7 before it is embedded in the pavement; and

Fig. 9 is a plan view of a stop sign made up by using the marker strip material described herein.

The marker forming the subject matter hereof comprises a main body portion 1, that is the visible portion of the marker and that is anchored in place by a depending portion 2, that is secured in place in a suitable groove 3, formed in the pavement where the marker is applied, as shown in the accompanying drawings. The marker strip is anchored in place by suitable expander plugs 4, as particularly shown in Fig. 4.

In the body portion of the marker strip, a series of spaced apertures 5 are formed along the median portion thereof. The end portions of the strip are preferably rounded as at 6. The edge portions 7 of the strip that overlie the pavement are also preferably slightly rounded as indicated at 8. The end portions may also be cut straight across, as shown in Fig. 9, if such is desirable.

The depending anchor portion 2 is formed integral with the body portion, and preferably comprises a pair of spaced flanges 9, shown in Fig. 3, as they appear prior to installation. The groove formed by the spaced flanges 9 opens upwardly 80 into the apertures 5. The longitudinal end portions of these flanges may be connected if desired to provide better anchorage at the ends of the strip.

The marker is locked in place by the use of 85 suitable expander or anchor plugs 4 embodying a barrel shaped expander portion 11 surmounted by a cap portion 12 that is formed integral therewith. These plugs are preferably made of hard rubber, so that they will wear down at 90 substantially the same rate as the marker strip. Any desired material, such as metal, rubber composition, or other material may be used, however, with good results.

In the preferred embodiment of this invention 95 the depending anchor portion of the marker strip is housed in the pavement by a groove 3 having upwardly converging walls 14 terminating in overhanging shoulders 15 and preferably provided with slightly raised and outwardly declining edge portions 16 of the same length as the anchor portions of the marker strip.

The marker strip is very quickly and easily installed. The anchor portion 2 of the strip is dropped into the groove 3 and the anchor plugs 105 4 are forced into position between the spaced flanges 9 by pressure applied upon the top of the cap portion 12. The anchor plugs are inserted through the apertures 5 of the body portion.

The insertion of the anchor plug places the flanges of the anchor portions of the marker strip into permanent compression against the side walls of the pavement groove, thereby securing 5 the marker strip into place and forming substantially a water and dust-proof seal for the mouth of the groove 3. The plug, being of rigid material, supports such weights as are applied upon its cap portions without substantial 10 vertical displacement, thereby preserving the seal of apertures 5 and the seal at the mouth of the groove.

It will readily be seen that this marker strip easily adapts itself to several useful modifications.

One such modification is shown in Fig. 9. The series of letters here shown, forming the conventional stop sign, are built up of marker strip material such as that shown in Fig. 3, or these individual letters, or parts thereof, may be molded 15 to form.

Further modification of the marker strip may be advisable in regions of heavy traffic or excessive moisture and dust condition wherein the depending anchor portion of the marker strip 20 is of solid construction with openings therein below and connected with the apertures in the body portion. The anchor plugs are forced into these openings in the manner described. Also the edge of the groove may be level or uninclined, 25 as shown in Fig. 6, or the groove may be replaced by a row of holes into each of which an anchor portion with its accompanying expansion plug is received.

It may be desirable to reinforce the side walls 30 and shoulders of the groove 3 by the use of a suitable metal liner 17 that is embedded in the concrete of the road structure, as shown in Figs. 6 and 7. The form shown in Fig. 6 is preferably provided with anchor tongues 18. The liner 35 form shown in Figs. 7 and 8 comprises a pair of side portions 19 and 20 that are suitably spaced by a bottom member 21 that is welded thereto. The liner metal is preferably of a character that 40 will not corrode or rust under service conditions.

The marker strip is preferably made of rubber composition, such as cushion tire or tread rubber stock.

The expansion inserts are preferably formed 50 of hard rubber, or rubber and fabric composition, or non-corrosive metal.

Further adaptations of this marker would be as bumpers on unloading platforms, corners of buildings, or other points where protection is 55 desirable.

Furthermore, it is to be understood that the embodiments of the invention shown and described, are presented for purposes of illustration, and that various modifications of the disclosure can be made without departing from my invention as defined in the appended claims.

What I claim is:

1. A road marker for use in combination with a surface having a recess therein provided with 55 overhanging edge portions, comprising a body portion, a depending anchor portion composed of elastic, deformable material, an aperture through said body portion communicating with an aperture in the anchor portion, and a plug insertable through the aperture of the body portion into the aperture of the anchor portion, said plug being formed with a bulging portion for materially enlarging the lateral dimension of the anchor portion to secure the marker in place within the recess in the surface to be marked.

2. A road marker for use in combination with a surface having a groove therein provided with overhanging edge portions, comprising a body portion of desired shape and a depending anchor portion having an elongated aperture, longitudinally spaced apertures through said body portion communicating with the aperture in the anchor portion, and a plurality of plugs insertable through the apertures of the body portion into the aperture of the anchor portion, each plug having a bulging portion for materially enlarging the lateral dimension of the anchor portion to secure the marker in place within the groove in the surface to be marked.

3. A road marker for use in combination with a surface having a groove therein provided with overhanging edge portions, comprising a body portion and a depending anchor portion composed of elastic deformable material, apertures through said body portion communicating with an aperture in the anchor portion, and plugs insertable through the apertures of the body portion into the aperture of the anchor portion, each plug having a bulging portion for materially enlarging the lateral dimension of the anchor portion to secure the marker in place within the groove in the surface to be marked. 95

4. The combination with a surface having a groove therein, of an insert of metal permanently embedded within said groove and provided with overhanging shoulder portions at the mouth of the groove, and a marker comprising a deformable rubber body portion, a depending anchor portion carried by the body portion and housed in said metal insert, apertures through 100 said body portion communicating with an aperture in the anchor portion, and means insertable through said body portion for materially enlarging the lateral dimension of the anchor portion to secure the marker in place within the groove in the surface to be marked.

4. The combination with a surface having a groove therein, of an insert of metal permanently embedded within said groove and provided with overhanging shoulder portions at the mouth of the groove, and a marker comprising a deformable rubber body portion, a depending anchor portion carried by the body portion and housed in said metal insert, apertures through 105 said body portion communicating with an aperture in the anchor portion, and means insertable through said body portion for materially enlarging the lateral dimension of the anchor portion to secure the marker in place within the groove in the surface to be marked. 110

5. An elastic rubber road marker for use in combination with a surface having a groove therein provided with overhanging edge portions, comprising a body portion, a depending anchor portion adapted to be received in said groove and having side members, apertures through said body portion communicating with the space between the side members of the anchor portion, and means insertable through the body portion into the space between the side members of the depending anchor portion for materially enlarging the lateral dimension of the anchor portion to secure the marker in place. 115

6. A rubber road marker for use in combination with a surface having a groove therein provided with overhanging edge portions, comprising a body portion, a deformable anchor portion integral therewith and having spaced side members, apertures through said body portion communicating with the spaces between said side members, and a plug insertable through the apertures of the body portion having bulging portions engageable with the side members for laterally expanding the anchor portion to form 120 a substantially water-tight seal. 125

7. The combination with a pavement having a groove in the surface thereof with upwardly converging walls, of a metal liner permanently disposed within said groove, and a flexible marker of elastic rubber composition material comprising a body portion projecting laterally beyond the edges of said groove, a depending anchor portion integral with the body portion and housed within 130 135

140

145

15

5 said metal insert, said body and anchor portions of said marker having apertures extending therethrough from the surface of said body portion, and means insertable through said apertures for materially enlarging the lateral dimension of the anchor portion and serving to compress the material of said anchor portion to secure the marker in place within the groove.

8. A road marker for use in combination with the crowned portion of a surface having a groove formed along said crown, comprising an apertured rubber body portion having a lower face converging upwardly inwardly of the lateral edges of said body portion, a deformable anchor portion continuously apertured with said body portion and of material continuously homogeneous with said body portion and a solid substantially barrel-shaped plug of maximum diameter greater than that of the aperture formed in said anchor portion.

9. A surface marker of elastic rubber, comprising a body portion having spaced apertures therein, an expansible anchor portion integral with the body portion and having an aperture aligned with each of the apertures of the body portion, said aperture in the anchor portion having a restricted neck portion at its junction with the apertures in the body portion, and expander plugs adapted to be inserted in said apertures, each plug having an end portion of a size to fit in an aperture of the body portion and a bulging portion for entry into the aperture of the expansible anchor portion for laterally distending said anchor portion.

10. The combination with a pavement having a marker receiving recess provided with overhanging edge portions at the top thereof, of an elastic rubber marker having a body portion of greater width than the opening and a depending anchor portion of a size to enter the recess between the overhanging edges thereof, said marker having an aperture from the top thereof through the body into

the anchor portion, and a tapering expanding plug having a portion of greater transverse dimension than the aperture in the anchor portion of the marker adapted to be inserted through said body portion and into the anchor portion to expand said anchor portion beneath the overhanging edges of the recess.

11. A road marker for use in combination with a surface having a groove therein provided with overhanging edge portions, comprising an elongated body portion of greater width than the groove and a depending longitudinal anchor portion of a width to enter the groove between the overhanging edges thereof, apertures extending through the body portion, each communicating with an aperture in the anchor portion, plugs insertable through the apertures of the body portion into the anchor portion, each plug having a portion of greater transverse dimension than the aperture in the anchor portion whereby the plugs expand the anchor portion laterally and compress the same in the recess beneath the overhanging edges thereof.

12. A road marker for use in combination with a surface having a groove therein provided with overhanging edge portions, comprising an elongated body portion of greater width than the groove and a depending longitudinal anchor portion of a width to enter the groove between the overhanging edges thereof, apertures extending through the body portion, each communicating with an aperture in the anchor portion, plugs insertable through the apertures of the body portion into the anchor portion, each plug having an enlarged portion intermediate its ends for expanding said anchor portion laterally and compressing the same in the recess beneath the overhanging edges thereof and an upper end portion of a size to substantially fit in the aperture of the body portion.
